UNITED STATES PATENT OFFICE.

STANISLAW LABEDZKI, OF PHILADELPHIA, PENNSYLVANIA.

HOT-WATER HEATER.

1,118,656.

Specification of Letters Patent. Patented Nov. 24, 1914.

Application filed April 2, 1914. Serial No. 829,081.

To all whom it may concern:

Be it known that I, STANISLAW LABEDZKI, subject of the Czar of Russia, residing at Philadelphia, in the county of Philadelphia and State of Pennsylvania, have invented 5 certain new and useful Improvements in Hot-Water Heaters; and I do declare the following to be a full, clear, and exact description of the invention, such as will enable others skilled in the art to which it 10 pertains to make and use the same.

My invention relates to improvements in hot-water heaters.

The primary object of the invention is to 15 provide a simple, strong and efficient water heater. To the above end, I employ a water back for application to the stove, a superheating tank above the stove, an outlet from said superheating tank, an inlet into said 20 water back and a plurality of pipes establishing communication between said water back and said superheating tank.

With the above object in view, my invention resides in the features of construction 25 and combination herein described and claimed and shown in the drawings wherein:—

Figure 1 is an enlarged vertical section through the range and heating tank; Fig. 30 2 is a horizontal section on the line 3—3 of Fig. 1; Fig. 3 is a perspective view of the water back; Figs. 4 and 5 are detail horizontal sections taken on the lines 5—5 and 6—6 of Fig. 1 respectively; Fig. 6 is a horizontal section showing a different form of water back for application to a stove constructed for the use of both gas and solid 35 fuel; Fig. 7 is a perspective view of the water back removed; and Figs. 8 and 9 are 40 transverse sections taken upon the lines 9—9 and 10—10 of Fig. 7.

In the first five figures of the drawings, I have shown my invention as applied to a 45 cooking stove or range R, said range comprising the usual rectangular casing C, fire-box F, oven O, smoke discharge opening o, smoke flue f leading from the fire-box to 50 said smoke discharge opening, a fuel supply door D into the upper end of said fire-box, a draft damper D' above the door D, and a door d into the oven.

The construction of the stove forms no 55 part of the present invention but it is expedient, in order to render the proper co- action possible, that the fire-box F should extend transversely across the upper por-

tion of one end of the stove and that the opening o be formed in the rear portion of the top of said stove.

Coming now more particularly to details 60 of the invention, the numeral 1 designates a hollow rectangular water back which is applied to the rear side of the range R and completely takes the place of the usual metal back therein. The back 1 is provided, on 65 one of its uppermost corners, with a forwardly projecting rectangular extension 2, said extension being also of hollow construction and communicating at its forward end with the interior of a hollow rectangular portion 3 which extends transversely inward therefrom and underlies the door opening which is normally closed by the door D. When the parts are in proper position, the under sides of the portions 2 and 70 3 rest upon the grate G and are supported by any suitable fastening means. The uppermost portion of the back 1 is provided, 75 preferably at its central portion, with a substantially semi-cylindrical extension 4 80 which projects rearwardly therefrom and thus forms a substantially semi-cylindrical smoke passage 5 which terminates flush with the bottom of the smoke flue f, at its lower end, while its upper end communi- 85 cates with the rearmost portion of the opening o. As clearly shown in Fig. 1, the inner and outer walls of the water back 1 are so spaced as to provide a circulating passage entirely around the rear wall of the 90 smoke passage 5. By this arrangement and construction of the water back and its various extensions, a large heating area is provided, all heat within the oven O, the fire-box F and that passing through the 95 flue f, being utilized for the purpose of heating the water in said water back.

Rising from the top of the range R and disposed above the opening o, is a cylindrical superheating tank 6, said tank having 100 upper and lower partitions 7 and 8 which are connected by smoke flues 9, said partitions forming upper and lower smoke chambers 10 and 11, the chamber 11 being located directly over the top of the range and the 105 chamber 10 being closed by a solid top 12 and having a discharge opening 13 between which and the chimney 14 a pipe 15 establishes communication. As clearly shown in Figs. 1 and 4, an upright pipe 16 rises from 110 the space between the partitions 7 and 8 and projects upwardly through the chamber

10 and through the top 12, said pipe being connected by means of an elbow 17 to a hot water discharge pipe not shown.

- For the purpose of admitting water into the interior of the back 1, I employ an inlet pipe 19 which leads from any suitable water pressure supply and is provided with a cut off valve 20 adjacent its connection to said back. When the valve 20 is opened, the interior of the back 1 will of course be filled with water which will now become heated from the action of the heat from the stove as before described. It is a well known fact that heated water will rise and therefore I have provided a plurality of pipes 21 which enter the offset portion 4 of the back 1 and the interior of the tank 6, between the partitions 7 and 8, said pipes entering these parts at different levels as clearly shown in Fig. 1. Thus it will be seen that the heated water will rise through said pipes and into the interior of the superheating tank 6 where it will be further heated by the action of the smoke passing upwardly therethrough and will then rise through the pipe 16 and will flow into the outlet pipe. From the outlet pipe it may be conducted, through suitable connections, to a number of radiators from which it then returns to the pipe 19 through return pipes which lead from the various radiators to a main return pipe which may be connected, between the valve 20 and the back 1, with the pipe 19. Thus it will be seen that the water, heated by the parts mounted upon the range R, will circulate through the various feed and return pipes and the radiators disposed therein and will again return to the interior of the water back 1 to be reheated.
- I intend to not only employ my improved heating system for the purpose of furnishing heat to the various radiators, but to also supply hot water to the various sinks, washstands and tubs in the building.
- When any one of the spigots is opened, it will be readily seen that some of the water within the system will be exhausted. During the day however, the valve 20 is left open and the water, under pressure, flowing through the pipe 19, will immediately refill the entire system. In case the water within the system becomes overheated and abnormally expanded, the pipe 19 will also serve as a partial outlet therefor and will prevent bursting of certain parts of the system.
- I also provide the ashpit of the stove with an outlet funnel F' whereby the ashes may be conducted to the basement.
- In Figs. 6 to 9 inclusive, I have shown the form of water back which I may well employ in connection with a cook stove having a portion for the use of gas and also a fire-box for consuming wood or coal. In applying the waterback to this form of stove, I construct the same in such a manner as to

provide a rectangular portion 50 for insertion into the fire-box, the side and end walls of said portion being of hollow formation, the rear end wall 51 forming the rear end of the fire-box F while the front 70 wall 52 is notched upon its upper end as indicated at 52' in order that no obstruction may occur between the draft controlling damper plate P and the interior of the firebox. The inner wall 53 of the rectangular 75 portion 50, is reduced in height at its rear end and is provided with a laterally extending portion 54 which is of semi-circular contour at its rear end and is entirely surrounded by an upright wall 55, the extension 54, the wall 55 and in fact, the entire structure, so far described, being of hollow formation, thus providing a large heating area for the water which is fed thereto through an inlet pipe 19' and is discharged 80 therefrom through a number of outlet pipes 21' from which it enters the superheating tank 6 in the hereinbefore described manner. By constructing the device in the last described manner, it will be seen that a rearwardly extending portion of substantially 90 semi-cylindrical contour is provided, said portion resembling the portion 4 of the previously described form of the invention and that the space between the lateral extension 95 54 and the top of the stove, constitutes an outwardly and upwardly extending draft flue. When this form of the invention is in position upon the stove, the semi-cylindrical extension 4' underlies the rearmost portion 100 of the smoke opening in the top of said stove.

It will be noted that the heat from the gas burners B will act, to a certain degree, to heat the water within the receptacle but that the majority of the heating will be done by the fire within the fire-box F.

From the foregoing description, taken in connection with the accompanying drawings, it will be seen that I have produced 110 a comparatively simple yet extremely efficient heating system and have provided means which compensate for overheating of the water and which serve to keep the system full at all times.

I may here explain that I provide a plurality of pipes 21, connecting the water back 1 with the superheating tank 6, for the purpose of preventing the system from "hammering," said pipes effectually overcoming 120 this objectionable feature.

Although I have described my invention with considerable minuteness, I do not wish to be limited to details of construction and arrangement of parts otherwise than as amplified in the appended claims.

Having thus described my invention, what I claim as new and desire to secure by Letters Patent is:—

1. The combination with a range, of a 120

- water back forming the entire rear side thereof and having a portion partially surrounding the fire-box of the stove and having a rearwardly projecting extension, a 5 superheating tank disposed above the smoke outlet of said stove and having upper and lower smoke chambers and an intermediate water receptacle, a smoke passage leading from said extension through said tank and 10 discharging near the upper end thereof, a water passage from said water back to said superheating tank, an outlet from the latter and an inlet into said back.
2. The combination with a range having 15 a smoke outlet opening in the rear edge of its top and a laterally extending smoke flue in communication with said opening, of a water back affixed to said range and forming the entire rear side of said range and 20 underlying said top, said back having a portion partially surrounding the fire-box thereof and a substantially semi-cylindrical extension at the rear side of the back and underlying the rear portion of the smoke 25 flue.
3. The combination with a range having a smoke outlet opening in its top, a water back forming the entire rear side of the stove and having a portion partially surrounding the fire-box thereof, a substantially semi-cylindrical extension projecting 30 outwardly from the upper edge of said back, said extension forming a substantially semi-cylindrical smoke flue disposed beneath the rear portion of said opening, a cylindrical 35 superheating tank disposed above said opening and having smoke chambers in its upper and lower ends and a water receptacle be-
- tween the two, an outlet from the top of said receptacle, a number of smoke flues es- 40 tablishing communication between said smoke chambers, the lowermost of the latter being closed by the top of the stove and the uppermost having a smoke outlet, and a pipe forming communication between the 45 water chamber of said tank and said semi-cylindrical extension.
4. The combination with a range having a smoke outlet in the rear portion of its top, of a water back constituting the back to the 50 fire-box and having a portion partially surrounding the same, a substantially semi-cylindrical extension on the rear side of the back and underlying the rear portion of the smoke outlet, said extension forming com- 55 munication between the fire-box and the outlet.
5. The combination with a range having a smoke outlet in the rear portion of its top, of a water back constituting the back to 60 the fire-box and having a portion partially surrounding the same, a hollow substantially semi-cylindrical extension on the upper edge of the back, said extension being united at its lower end with the back by 65 an inwardly extending wall and its upper end and inner side being open, said upper end underlying the rear portion of the smoke outlet.

In testimony whereof I have hereunto 70 set my hand in presence of two subscribing witnesses.

STANISTAW LABEDZKI.
